B. W. Brueel

UNITED STATES PATENT OFFICE.

B. W. BRUEL, OF BELOIT, WISCONSIN.

MOP-HOLDER.

Specification of Letters Patent No. 29,566, dated August 14, 1860.

To all whom it may concern:

Be it known that I, B. W. BRUEL, of Beloit, in the county of Rock, in the State of Wisconsin, have invented certain new and useful Improvements in Mop-Holders; and I do hereby declare that the following is a full and exact description thereof, reference being had to the accompanying drawings, and to the letters of reference marked thereon.

My invention relates to a novel method of constructing mop sticks, or holders, and consists in the employment of two swivel clamping jaws arranged on the ends of a bifurcated handle furnished with the usual, clasping, or securing band, as will be hereinafter fully described, whereby the swab mop, or material clasped by the holder will always be firmly held along the whole length of the jaws as will be presently explained.

To enable those skilled in the art to make and use my invention, I will proceed to describe its construction and operation, referring by letters to the accompanying drawings forming part of this specification and, in which—

Figure 1, represents in perspective my improved mop holder. Fig. 2, is a longitudinal section through the center of the same on the line y, y , of Fig. 1. Fig. 3, is a cross section at the line x, x , Fig. 1, and Fig. 4, is a similar section illustrating the jaws in a changed position.

In the different figures the same parts are indicated by the same letters.

A, is a bifurcated handle on the ends of the forks of which are formed two studs, or cylindrical tenons, a, a , on which are hung the clamping jaws B, B^2 . Said jaws are so arranged on the tenons, a, a , as to turn freely around the said tenons—but are prevented from sliding longitudinally on them by means of retaining pins, c, c , which pass through the jaws and into grooves, or slots formed in the circumferences of said tenons.

C, illustrates the mop, or cloth which may be of any material desired to be used. D, is a sliding ring which is forced along on the bifurcated handle, A, and clasps the two jaws, B, B^2 together embracing the mop, C.

Previous to my invention the jaws, B, B^2 have been fixed rigidly to the ends of the bifurcated handle so that when the two legs

of the handle or holder were forced together the jaws would always approach each other 55 in parallel planes.

In an apparatus thus constructed, the mop, or cloth inserted between the jaws would not be clasped and held during the whole length of the jaws unless the cloth was of an even 60 or uniform thickness between the jaws. In practice this has proved a great objection, since different cloths or mopping materials often used in the same holder at different times, and if great care is not taken and 65 much time expended to have a layer of material of uniform thickness between the jaws, the jaws will clamp down tightly on the thickest side, and the thin side of the mop cloth will pull out from between the jaws 70 and occasion much annoyance.

At Fig. 3, it will be seen the jaws are clamped on a uniform thickness along their entire length, while at Fig. 4, they are illustrated as clamped down onto a layer of mop 75 cloth which is about twice as thick at one end as it is at the other. And it will be seen that by having the jaws B, B^2 hung so as to swivel they will adjust themselves in the proper relation to each other, and confine 80 perfectly at both ends the mop cloth though the latter may be much thicker at one end than at the other—and it will be seen that although my improved apparatus possesses great practical advantages over those here- 85 tofore made it is exceedingly simple, and the cost of manufacture will not exceed that of those which are far less preferable to the public.

Having described the construction and 90 operation of my improved mop holder, what I claim as new, and desire to secure by Letters Patent, is—

The slotted hole and pin by which the jaws B, B^2 are rendered self adjusting in 95 combination with the bifurcated handle, A, and retaining clasp—the whole arranged and operating as hereinbefore described for the purpose set forth.

In testimony whereof I have hereunto set 100 my hand and affixed my seal this twenty-eighth day of June, 1860.

B. W. BRUEL. [L.S.]
